J. W. COAST, JR.
ART OF CRACKING HYDROCARBONS.
APPLICATION FILED SEPT. 27, 1917.

1,370,881.

Patented Mar. 8, 1921

UNITED STATES PATENT OFFICE.

JOHN W. COAST, JR., OF TULSA, OKLAHOMA, ASSIGNOR TO THE PROCESS COMPANY, OF TULSA, OKLAHOMA, A CORPORATION OF MARYLAND.

ART OF CRACKING HYDROCARBONS.

1,370,881.

Specification of Letters Patent.

Patented Mar. 8, 1921.

Application filed September 27, 1917. Serial No. 193,454.

To all whom it may concern:

Be it known that I, JOHN W. COAST, Jr., a citizen of the United States of America, a resident of Tulsa, in the county of Tulsa, 5 State of Oklahoma, have invented certain new and useful Improvements in the Art of Cracking Hydrocarbons, of which the following is a full, clear, and exact description, reference being had to the accompanying 10 drawing, forming a part of this specification.

This invention relates to improvements in the art of cracking hydrocarbons, the main object being to protect cracking stills from 15 the injurious effects of carbon or tarry substances known in the art as coke and coke-forming matter.

Another object is to circulate the oil undergoing distillation, thereby economizing 20 in the use of fuel, maintaining the oil at a substantially uniform temperature throughout the still, and enabling the temperature to be raised quickly at the beginning of the distilling operation.

25 A further object is to enable the apparatus to remain in service for a considerable period of time without cooling the still or removing the residue.

In the preferred form of the invention, all 30 of these desirable results are accomplished by circulating a small stream of the hydrocarbon liquid from the heated lower portion of the still, through a screen or filter wherein the coke-forming matter is separated 35 from the oil, and then discharging the filtered oil into the main body of oil. While the oil is undergoing distillation under high pressure and at a high temperature, the heavy coke-forming fractions drop by 40 gravity to the bottom of the still, and in following the ordinary practice, the coke or carbon is permitted to accumulate on the still bottom, directly above the fire. One of the important problems in this art lies in the 45 elimination of large bodies of coke or carbon, from the hottest parts of cracking stills. The coke or carbon is an insulating substance, preventing the free transmission of heat from the still bottom to the oil, thus 50 decreasing the efficiency of the heating medium, and when a sufficient quantity of the insulating substance accumulates in the still, the still bottom becomes red hot. Some immediate steps must then be taken to avoid a 55 rupture at the overheated portion of the

still. Owing to the high pressure and temperature of the oil in the still, the accumulations of coke or carbon have, heretofore, rendered cracking operations quite dangerous.

The present invention entirely eliminates 60 this danger, and at the same time obtains a number of other very important advantages, all of which are highly desirable in the manufacture of gasoline from relatively heavy 65 petroleum distillates and residues.

Figure I is a diagrammatical view of a cracking apparatus adapted for use in carrying out the new method.

Fig. II is an enlarged longitudinal section 70 of the still.

Fig. III is an enlarged section of the screen or filter.

In the apparatus shown to illustrate the invention, a large cylindrical still 1 is arranged above a heating chamber 2, and connected by means of a vapor pipe 3, to an air cooled reflux condenser 4. 5 designates a vapor pipe leading from the reflux condenser 4 to a main condensing coil 6, from 75 which the low boiling point product is recovered. The condensing coil 6 is preferably arranged in a water tank 7.

The apparatus herein shown is particularly adapted for use in cracking high boiling point products of distillation such, for example, as distillates or residues resulting from the distillation of crude petroleum. The substance to be treated is introduced into the still in any suitable manner, and 90 any desired pressure may be obtained by regulating a valve 8, preferably located in the vapor pipe 5. The pressure in the still is preferably greater than 50 pounds per square inch, for example, about 80 pounds 95 per square inch, and the temperature of the contents of the still preferably ranges from about 600° F. to 800° F. Heat generated in the heating chamber 2 is transmitted directly through the still bottom to the liquid 100 contents of the still. The low boiling point vapors passing from the liquid, flow through the vapor pipe 3 and reflux condenser 4 to the pipe 5, leading to the main condenser 6 from which the low boiling point product is 105 recovered. The relatively high boiling point fractions are condensed in the vapor pipe 3 or in the condenser 4, such fractions being returned, by gravity, through the vapor pipe 3. The heating chamber 2 may be pro- 110

vided with a grate 8 on which a bed of fuel is maintained.

In the preferred form of the invention, an elongated intake pipe 9, arranged in the lower portion of the still, is provided with inlet ports 10 at various points throughout its length. 11 designates a rotary pump connected to the intake pipe 9, and provided with a discharge pipe 12 leading to a screen 10 or filter A, the latter being provided with a discharge pipe 13. The pump and filter, as well as the pipes 9, 12 and 13, are preferably located in the still and submerged in the liquid contents thereof. A power shaft 14, passing through a stuffing box 15 at one end of the still, may be rotated to actuate the pump 11. A pinion 16 fixed to the inner end of shaft 14, meshes with an operating wheel 17 on the pump, and this shaft 14 may be rotated by transmitting power to a wheel 18 at the exterior of the still.

The filter, or strainer, A comprises a screen 19 arranged in a housing 20 wherein the coke-forming matter is separated from the oil. The filter or strainer may also include a layer of mineral wool 21 arranged above the screen 19, and a layer of fullers' earth 22 between the mineral wool and the top wall of the housing 20. To obtain the highest efficiency, a large filter should be used and its capacity should enable the distillation to be carried on for a considerable period of time without removing the coke-forming matter from the filter.

While the oil is undergoing distillation, the rotary pump 11 is operated continually, thereby drawing oil and coke-forming matter through the ports 10 in the intake pipe 40 near the hot still bottom, the stream of oil and coke-forming matter being drawn to the pump 11, and discharged through the pipe 12, to the filter A. The free carbon, or coke-forming matter, accumulates in the filter A, and the filtered oil is constantly discharged from the pipe 13 to the main body of oil in the still. A relatively small stream of oil is thus maintained in circulation in the large main body of oil, and the coke-forming matter is filtered from the small internal stream and collected in the housing 20, instead of being permitted to accumulate on the hot still bottom. It will

now be understood that this invention entirely eliminates the danger usually due to 55 an accumulation of coke or carbon in the still, thereby greatly increasing the life of the still, increasing the efficiency by taking away the heat insulating matter from the place at which the heat is transmitted 60 through the still, and enabling the still to be recharged and run continuously for a considerable period of time without cooling the apparatus, and without removing the residue. 65

By forcibly circulating a relatively small stream of oil in the main body of the oil, as herein disclosed, a general circulation of all of the oil is maintained. The hot oil entering the pipe 9 is drawn toward one 70 end of the still, then upwardly to the pump and thereafter discharged toward the opposite end of the still. Owing to the manner in which the oil is circulated, a substantially uniform temperature is maintained at all 75 points throughout the oil, the heat being transmitted quickly from the still bottom to the entire body of oil. This is an advantage at all times during the distilling operation and more particularly at the beginning of the operation, at which time it is desirable to obtain the necessary high temperature throughout the still as quickly as possible. 80

I claim:—

In the art of cracking petroleum hydrocarbons, the method which comprises confining a body of hydrocarbon oil in a cracking still, heating the bottom of the still to vaporize the oil, condensing the vapor, 90 maintaining the contents of the still under pressure, forcing a stream of oil and coke-forming matter from the heated lower portion of the still, filtering said stream to separate the coke-forming matter from the oil, 95 at the same time maintaining the stream of oil and the coke-forming matter at the temperature of the contents of the still and discharging the filtered oil into the main body of oil in the still, the circulating stream being completely inclosed within the still to avoid cooling of the oil. 100

In testimony that I claim the foregoing I hereunto affix my signature.

JOHN W. COAST, JR.
